(57) **CLAIM**

The ornamental design for a screening apparatus, as shown and described.

DESCRIPTION

FIG. 1 is a front perspective view of the screening apparatus showing my new design;

FIG. 2 is a rear perspective view of the screening apparatus of FIG. 1;

FIG. 3 is a left-side elevation view of FIG. 1;

FIG. 4 is a right-side elevation view of FIG. 1;

FIG. 5 is a top plan view of FIG. 1;

FIG. 6 is a front elevation view of FIG. 1;

FIG. 7 is a rear elevation view of FIG. 1;

FIG. 8 is an enlarged view of the area designated 8 in FIG. 1; and,

FIG. 9 is an enlarged view of the area designated 9 in FIG. 1. A bottom view of the screening apparatus constitutes no part of the claimed design.

The broken lines are included for the purpose of illustrating portions of the screening apparatus that form no part of the claimed design.
